W. F. HARVEY

SHINGLE

Filed June 29, 1922

UNITED STATES PATENT OFFICE.

WILLIAM F. HARVEY, OF EAST PATCHOGUE, NEW YORK.

SHINGLE.

Application filed June 29, 1922. Serial No. 571,664.

To all whom it may concern:

Be it known that I, WILLIAM F. HARVEY, a citizen of the United States, and residing at East Patchogue, Long Island, in the county of Suffolk and State of New York, have invented certain new and useful Improvements in Shingles, of which the following is a specification, such as will enable those skilled in the art to which it appertains to make and use the same.

This invention relates to shingles and particularly to composition shingles, or shingles composed of pitch, rubber or other compositions, and the object of the invention is to provide a shingle of the class specified the opposite side edges of which are provided with flanges bent in opposite directions or inwardly upon the top and bottom faces of the shingles so that when said shingles are placed one upon another the bottom flanges of one shingle will interlock with the top flanges of adjacent shingles; a further object being to provide means for reinforcing and strengthening the shingles where interlocked; a still further object being to provide a shingle construction of the class specified which will prevent the passage of rain or other moisture inwardly around the separate shingles; and with these and other objects in view the invention consists in a shingle of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a plan view showing a number of my improved shingles coupled together;

Fig. 2 a section on the line 2—2 of Fig.

45 1 on an enlarged scale;

Fig. 3 a plan view of one of my improved shingles on an enlarged scale;

Fig. 4 a sectional detail view on the line 4—4 of Fig. 1 and on an enlarged scale; and

50 Fig. 5 is a bottom plan view of one corner portion of the shingle shown in Fig. 3 of the drawing and on an enlarged scale.

My improved shingle is preferably composed of a rectangular sheet of suitable composition board 5, or a board composed of waterproof composition material which

is light, flexible and yet strong and durable, and two sides edges of said board are cut out to form flanges 6 which are folded upon the top face of the board and the corner portions of which are cut at an angle as shown at 7, and the adjacent corners of which are joined by a binding clip 8, the other and opposite side edges of the board are cut and folded to form flanges 9 similar to the flanges 6 and which are folded inwardly upon the bottom face of the board and the adjacent edges of which are joined by a clip 10 having a projecting tongue 11, which is adapted to cooperate with the clip 8 of another board or shingle in assembling the same.

In mounting my improved shingles in connection with a roof or other structure, the corner portion 12 of the shingles are directed downwardly and one row of said shingles are placed side by side and in the same longitudinal plane, after which another row of shingles is mounted upon the first named shingles, and the flanges 9 on the bottom face of said last named shingles are passed beneath and interlocked with the flanges 6 in the top face of the first named row, as clearly shown at 13 in Fig. 2 of the drawing, and this operation continues until the roof structures has been covered.

It will be noted on a consideration of Fig. 1 of the drawing that the third row, or the alternate rows of shingles are placed in the same vertical alinement as the first row of shingles, and in placing the third row of shingles in position the projecting tongues 11 of said shingles passes beneath the clips 8 on the flanges 6 of the first row of shingles and this serves to permanently retain the lower corner portion 12 of said third row of shingles against warping or raising from the roof structure, in other words, the interlocking of the tongues 11 with the clips 8 serves to retain and interlock the free corner portions 12 of the shingles with the adjacent shingles.

In securing the shingles in connection with the roof structure, nails or tacks 14 are passed through the upper and side corner portions of said shingles for holding said shingles in position, and these nails or tacks are located between the adjacent edges of the flanges 6 and 9 of said shingles and do not interfere with the interlocking of the separate shingles with each other.

It will also be noted on a consideration

of Fig. 1 of the drawing that in order to finish the lower edge of a roof or other structure, I place between the separate shingles of the lower row half shingles 5^a which are exactly the same as the other shingles merely cut transversely to provide two flanges on one side of said half shingle and a slight extension 5^b to form an accurate finish and similar half shingles may be 10 used in finishing the top edge of a roof structure, or the like, as well as the side edges thereof. It will also be apparent that by the use of my improved shingles as a facing for a roof or other structure, rain, 15 sleet, snow and the like cannot pass inwardly between the separate shingles and leak through such roof or other structure as is possible with shingles of this class, as now constructed, and it will also be understood 20 that the nails or other attaching devices are concealed and protected from the weather, and a shingle constructed as herein shown and described will render long and durable service and will also facilitate the 25 mounting of said shingles in connection with roof or other structure, it being understood that when a row or line of shingles have been properly placed, the remainder of said shingles will automatically assume 30 their proper position on the roof structure, if properly interlocked one with the other.

It will be understood that while I have shown certain details of construction for carrying my invention into effect and have 35 illustrated a specific application of the shingle, that I am not necessarily limited to the construction herein shown and described, and various changes therein and modifications thereof may be made, within 40 the scope of the appended claims, without departing from the spirit of my invention or sacrificing its advantages.

Having fully described my invention, what I claim as new and desire to secure 45 by Letters Patent, is:—

1. A shingle of the class described the opposite side edges of which are provided with flanges which extend inwardly upon the opposite side faces of said shingle, and 50 means for joining the adjacent edges of said flanges.

2. A shingle of the class described the opposite side edges of which are provided with flanges which extend inwardly upon the opposite side faces of said shingle, and 55 means for joining the adjacent edges of the flanges.

3. A shingle of the class described the opposite side edges of which are provided with flanges which extend inwardly upon the opposite side faces of said shingle, clips for joining the adjacent edges of the flanges, and one of said clips being provided with a projecting finger.

4. A shingle of the class described composed of a substantially rectangular sheet of composition material, two of the side edges of said sheet having flanges which lie upon the upper face of said sheet, the opposite edges of said sheet having flanges which lie on the bottom face of said sheet, the corner portions of said flanges being mitered, and means for connecting the flanges where mitered.

5. A shingle of the class described composed of a substantially rectangular sheet of composition material, two of the side edges of said sheet having flanges which lie upon the upper face of said sheet, the opposite edges of said sheet having flanges which lie on the bottom face of said sheet, the corner portions of said flanges being mitered, clips for joining the flanges where mitered and one of said clips being provided with a projecting finger.

6. A shingle of the class described, the opposite edges of which are provided with flanges which extend inwardly upon the opposite side faces of said shingle, and means at offset corner portions of said shingle and on the opposite faces thereof for interlocking the separate shingles one with another, when placed in position.

7. A shingle of the class described composed of a substantially rectangular sheet of composition material two of the side edges of said sheet having flanges, which lie upon the upper face of said sheet, the opposite edges of said sheet having flanges, which lie on the bottom face of said sheet, and means secured to the separate adjacent edges of said flanges at opposite corner portions of the shingle for interlocking the separate shingles one with another, when placed in position.

8. A shingle of the class described provided with inwardly turned flanges, and means independent of said flanges and secured thereto for joining the adjacent edges thereof.

In testimony that I claim the foregoing as my invention I have signed my name this 27th day of June 1922.

WILLIAM F. HARVEY.
